Primary Examiner — T. Chase Nelson*Assistant Examiner* — Mark Cavanna(74) *Attorney, Agent, or Firm* — Lathrop & Gage LLP(57) **CLAIM**

The ornamental design for a diagnostic cartridge reader, as shown and described.

DESCRIPTION

FIG. 1 is a front perspective view of the diagnostic cartridge reader, showing the new design;

FIG. 2 is a front elevation of the diagnostic cartridge reader; FIG. 3 is a side elevation of the diagnostic cartridge reader, an opposing side elevation of the diagnostic cartridge reader being a mirror image thereof;

FIG. 4 is an top plan view of the diagnostic cartridge reader; FIG. 5 is a rear elevation of the diagnostic cartridge reader; FIG. 6 is a bottom plan view of the diagnostic cartridge reader; and,

FIG. 7 is a rear perspective view of the diagnostic cartridge reader.

In all of FIGS. 1 through 7, dashed lines indicate environmental structure that forms no part of the claimed design.
